UNITED STATES PATENT OFFICE.

HERMANN LEMP, OF LYNN, MASSACHUSETTS, ASSIGNOR TO GENERAL ELECTRIC COMPANY,
A CORPORATION OF NEW YORK.

FLUE CONSTRUCTION FOR SELF-PROPELLED VEHICLES.

No. 876,980.

Specification of Letters Patent.

Patented Jan. 21, 1908.

Application filed May 3, 1904. Serial No. 206,208.

To all whom it may concern:

Be it known that I, HERMANN LEMP, a citizen of the United States, residing at Lynn, in the county of Essex and State of Massachusetts, have invented certain new and useful Improvements in Flue Construction for Self-Propelled Vehicles, of which the following is a specification.

The present invention relates to self-propelled vehicles and more especially to those driven by steam or other vapor.

The object of the invention is to improve the construction and arrangement of vaporizer flues whereby the efficiency of the vaporizer is increased and the effect of the draft on the burner made to bear a definite, or substantially definite, relation to the speed of the vehicle.

It is the usual practice to continuously employ a steam jet in one of the flues for creating a forced down draft, which jet may be supplied from the exhaust of the engine, or by live steam. In either case it means that the water in the steam thus employed is thrown away. By means of my invention a forced draft is created by the movement of the vehicle itself and in a degree corresponding to a large extent with the speed variations. In this manner no steam for draft purposes need be employed, and all of the exhaust may be returned to a condenser.

In carrying out the invention I place a boiler or vaporizer and burner in a position where they are readily accessible such, for example, as on the vehicle frame in front of the seat or seats. The vaporizer is supported so that it extends above and below the frame. The vaporizer is inclosed in a suitable casing, and situated in operative relation to the vaporizing surfaces and within the casing is a burner or fire chamber of suitable construction.

The casing is provided with a smoke-box or bonnet that communicates with an opening or passage through which the products of combustion pass. The walls forming the smoke-box or bonnet may be a continuation of the boiler casing, or separate therefrom. In both cases the communication from the boiler casing should be relatively free and unrestricted. The casing is also provided at a suitable point or points with respect to the burner with one or more openings for admitting air to support combustion. Commu-

nicating with the air-admitting opening or 55 openings is a flue which may take the form of a scoop with an open end which is so situated that it receives air currents induced by the movement of the vehicle. When the vehicle is standing still some air will be drawn 60 through the open end of the flue or scoop due to the action of the burner, and when the vehicle is started into motion a certain amount of air will be forced into the casing in addition to the amount due to the burner 65 action. As the movement of the vehicle becomes more rapid the amount of air forced into the fire chamber or burner space is correspondingly increased. In order to prevent the incoming air currents passing 70 through the flue or scoop from directly striking the burner flame, suitable deflectors are provided.

Communicating with the opening or passage leading from the smoke-bonnet which 75 discharges the products of combustion is an intake flue which occupies a horizontal or substantially horizontal position. This flue should be so constructed and arranged that the air currents entering it are not discharged into the said opening or passage, but act after the fashion of an ejector to increase the draft on the burner. On the other hand, it should also be so constructed and arranged that it will permit the products of 80 combustion to escape under natural draft, as for example when the vehicle is standing still or running so slowly that substantially no draft is created thereby. These results may be accomplished by having the front 85 end of the intake open, the said opening being in the same general direction as that of the scoop. I have found by practical operation that the results are satisfactory if the cross-sectional areas correspond or 90 approximately correspond, but do not wish to limit myself thereto. The larger the intake flue, the greater will be the forced draft, and the greater the amount of oil 95 which can be consumed with a corresponding increase in vapor energy. A second or discharge flue is also provided, which conveys the products of combustion escaping from the passage leading from the smoke bonnet to a suitable point below the vehicle frame 100 and preferably near the roadbed and discharges them. The cross-sectional area of the discharge flue should be great enough to 105

convey the air currents from the intake flue and the waste products of combustion from the vaporizer and burner without choking.

In order to further increase the effective action of the discharge flue, it is bent or deflected rearwardly so that the waste products of combustion, mingled with the air from the intake, will be deflected into a plane coinciding more or less with that of the air rushing past the open end of the flue, due to the motion of the vehicle, which increases the draft. I find it desirable to enlarge this discharge opening somewhat so as to increase the effect of said air currents. In order to prevent the air from the intake passing down through the smoke bonnet and vaporizer casing, a deflector plate is provided which may form a part of one or both flues, or it may be separate. The incoming air currents striking the deflector at the proper angle are deflected thereby into the discharging flue. A wall or separator plate separates the intake flue from the outlet of the smoke-box, and may for simplicity form a part or continuation of said flue. When the vehicle is climbing a hill or is subjected to especially heavy duty I may temporarily employ a steam jet in the discharge flue which receives live or exhaust steam as desired; or a blower may be connected to the flue in a manner to increase the draft, in which case all of the steam may go to the condenser as before.

It is to be especially noted that the intake flue located above the vaporizer and the flue or scoop discharging air into the fire chamber, are pointed in the same direction, since I regard this as an important feature of my invention. By this arrangement the effect of one flue is balanced by the other, and the effect of the burner increases or decreases as the wind varies, and the products of combustion are carried away from the occupants of the vehicle rather than towards them. Suppose the vehicle to be standing still with a strong wind blowing from the back, it cannot enter the flue or scoop discharging into the fire chamber owing to the closed rear end, and the products of combustion issuing from the intake flue will be carried forward away from the occupants. On the other hand if the wind is blowing from the front, the effect will be the same as though the vehicle was in operation and the waste products of combustion will be blown down underneath the vehicle body and dispersed. The air which passes in the flue or scoop at the bottom of the vaporizer balances that entering at the top, and consequently the action of the burner is not interfered with.

In the accompanying drawings, which illustrate one embodiment of my invention, Figure 1 is a partial elevation of an automobile with certain of the parts broken away to show the vaporizer and flues; Fig. 2 is a plan

view of the intake flue and vaporizer; Fig. 3 is a vertical section of the vaporizer and flue; and Fig. 4 is a sectional detail view of the flue or scoop which supplies air to the burner.

1 represents the frame of the vehicle which is supported by wheels 2, the rear wheels having been omitted to simplify the illustration.

3 represents the operator's seat, back of which may be located one or more passengers' seats.

Situated below the frame and at a point in advance of the operator's seat is a steam or other vapor engine 4 which propels the vehicle. Vapor is supplied to the engine by a vaporizer 5 which is carried by supports 6 from the main frame.

Situated above the vaporizer is an intake flue 7 and situated below the vaporizer and supplying air to the fire chamber is a flue or scoop 8. The intake flue and scoop 8 discharge into the downwardly-opening flue 9 which is provided with a detachable lower lower end or section 10 for facilitating the removal of the casing from the frame. This detachable section is secured in place by wing nuts 11 so that it can be taken off when it is desired to get at the engine. The lower end of the detachable section is expanded and inclined rearwardly at 12 and terminates in a horizontal plane to increase the draft on the fire chamber. In order to facilitate the removal of the parts, small doors 9' are provided adjacent to the nuts which secure the flue to the casing of the vaporizer.

The intake flue 7 is short in the vertical dimension and relatively long in the horizontal dimension, the object of this arrangement being to make it as unobtrusive as possible, and to make the front end of the vehicle relatively low. From the entering orifice the flue gradually changes its shape to a point substantially over the center of the vaporizer. In order to conceal the flue as much as possible, a hood 13 is provided which surrounds it and also the upper end of the vaporizer. The end of the hood adjacent to the seat is attached to a vertical support 14 which acts as a dash and also carries the necessary indicating instruments, such as 115 gages, indicators, etc. Located at the front of the vehicle and below the intake flue is a condenser 15 of suitable construction, into which the exhaust from the engine 4 discharges, and from the condenser the liquid 120 is returned to the vaporizer by suitable conduits.

Referring to Fig. 2, 16 represents the braces which are employed to support the upper and lower walls of the intake flue in 125 fixed relation. As shown these braces consist of thin plates occupying vertical positions and extending longitudinally of the flue, but other braces can be used. 17, shown in dotted lines, represents the orifice 130

leading from the smoke-box or bonnet and communicating with the flues, and 18 represents the deflector which is obliquely disposed relative to the center lines of the flues 5 and deflects the incoming currents of air into the downwardly opening flue for creating a forced draft. 12 represents the rearwardly flaring and detachable end on said flue.

Referring to Fig. 3, 20 represents the casing which incloses the vaporizing tubes 21, the latter being supported by bars or tubes 22 which extend from one side of the casing to the other. Situated above the vaporizer tubes, which tubes are preferably arranged 10 in sections, is a smoke-box or bonnet 23 that receives the products of combustion after the major portion of their heat has been given up in passing through the spaces between the boiler tubes. The waste products 15 of combustion from the smoke-box are discharged into the flue or passage 23' through the opening 17. The flue 23' is separated from the intake flue by a wall or partition 24 which prevents the incoming currents of air 20 from passing into the smoke-box. This action is further assisted by the deflector or baffle 18 which deflects the incoming currents of air, together with the waste products 25 of combustion, from the smoke-box into the downwardly-opening flue 9. The space between the inclined baffle plate 18 and the adjacent end of the flue or passage 23' forms an oblique connection between the flues 7 and 9. From the discharge end of 30 the passage or flue the gases discharge into this connection or chamber from which they 35 may pass freely either into the intake flue or the downwardly-opening flue, depending upon draft conditions. That is to say, when 40 currents of air are induced in the intake flue, due either to movement of the vehicle, or to the wind in case the vehicle is standing, the gases will pass into the downwardly-opening flue; when there are no currents of air in the 45 intake flue the gases or products of combustion will pass freely into the intake flue and discharge from the open end thereof at the front of the vehicle. Thus the passage 23' is a discharge flue common to the intake flue 7 50 and the discharge flue 9, and it serves to convey off all the products of combustion at all times. This is also an important feature of the invention, as it simplifies the construction and permits the natural draft to take 55 care of itself.

Situated below the vaporizer tubes and preferably inclosed by the vaporizer casing is a burner 25. The burner shown comprises one or more vaporizing tubes 26, a baffle 27 60 and a tube 28, which supplies vapor to a nozzle opening situated directly underneath the vaporizer. The burner is of the jet type and is intended to burn kerosene although other burner arrangements can be employed without departing from my invention. Situated

at the sides of the burner are downwardly-extending baffle plates 29, Fig. 4, which direct and assist in warming the incoming currents of air. 30 represents the base or bottom upon which the burner is mounted and 70 which coöperates with the plates 29 to prevent the air currents from passing directly to the burner. The air supply is received from one direction and is divided laterally into two currents by the plate or base 30 so that air is discharged into the bottom of the fire chamber at two points adjacent the sides. The combined area of the opening between the bafflers and the base should be great enough to supply the necessary amount of 80 air to support combustion at all times. In order to clean the burner a pin 31 is employed which is supported by a pivoted arm 32. Moving the arm up or down will cause the pin to move into or out of the burner orifice as 85 the case may be. Situated below the base of the burner and hinged thereto at 33 is a flue or scoop 8 which is closed at the bottom, sides and at one end. The front end opens in the same or substantially the same direction as the intake flue 7 and is so arranged that as the speed of the vehicle increases the amount of air forced into the burner will be 90 increased.

In order to temporarily increase the draft 95 on the burner, as for example when climbing a hill or moving very slowly under heavy duty, exhaust or high-pressure vapor may be admitted to the nozzle or jet 35 which extends into the downwardly-opening flue. 100 This nozzle is provided with an expanding lower end so as to impart a certain amount of velocity to the vapor employed to create an additional draft. I may use this nozzle or jet under the conditions mentioned, but I do 105 not intend to use it except in rare instances since the vapor which passes through it is lost.

In accordance with the provisions of the patent statutes, I have described the principle of operation of my invention, together with the apparatus which I now consider to represent the best embodiment thereof; but I desire to have it understood that the apparatus shown is merely illustrative, and that 110 the invention can be carried out by other means.

What I claim as new and desire to secure by Letters Patent of the United States, is,

1. In a self-propelled vehicle, the combination of an upright boiler provided with a fire chamber, a casing for the boiler having an outlet at the top for the products of combustion, a flue leading from the outlet to a point adjacent the edge of the casing, a substantially horizontal flue above the first flue which leads from the front of the vehicle and has its rear portion on top of the first flue, a third flue at the rear of the boiler and substantially at right angles to the first and sec- 120

125

130

ond flues with its discharge end directed toward the rear of the vehicle, and a chamber connecting the rear openings of the first and second flues with the inlet of the third flue
5 which permits a free passage of the contents of the first and second flues into the third when the vehicle is moving forward and of the contents of the first flue into the second when the vehicle is standing still or moving
10 backward.
2. In a self-propelled vehicle, the combination of a boiler having a fire chamber, a casing for the boiler provided with an outlet at the top for the gases from the fire chamber,
15 a flue leading from the outlet along the top of the casing to a point adjacent its edge, a second flue above the first which leads from the front of the vehicle with its rear portion on top of the first flue and its rear opening in substantially the same plane as that of the first flue, a third flue extending
20 downward at the rear of the casing, and a chamber connecting the adjacent ends of the flues and provided with an inclined wall
25 which directs air from the second flue across the opening of the first flue into the third when the vehicle is moving forward but permits a free outward passage of gases from the first flue through the second when the
30 vehicle is standing still or moving backward.
3. In a self-propelled vehicle, the combination of an upright boiler provided with a fire chamber having an air inlet directed toward the front of the vehicle, a casing for the
35 boiler having an opening in its top for the outward passage of the products of combustion from the fire chamber, a flue leading from the opening along the top of the casing to a point adjacent its edge, a second flue
40 leading from the front of the vehicle and having its rear portion over the first flue, a

third flue extending downward at the rear of the boiler with its inlet opening at substantially right angles to the openings in the rear ends of the first and second flues and its discharge opening directed toward the rear of the vehicle, and a chamber connecting the rear openings of the first and second flues with the inlet of the third which permits the contents of the first and second flues to pass into the third when the vehicle is moving forward and the contents of the first flue to pass through the second when the vehicle is standing still or moving backward.
45

4. In a self-propelled vehicle, the combination of a boiler having a fire chamber, a casing for the boiler having an opening at its top for the products of combustion, a flue leading from the opening along the top of the casing toward the rear of the vehicle, a second flue above and substantially parallel to the first which leads from the front of the vehicle, a third flue extending downward at the rear of the casing, a chamber connecting the adjacent ends of the flues and having an
60 inclined wall opposite said ends which directs air from the second flue across the opening of the first flue when the vehicle is moving forward to create a draft on the fire chamber and discharge the mixture of air
65 and combustion gases into the third flue, and a fourth flue which receives air at its front end and delivers it into the fire chamber at the sides thereof to augment the draft created by the second flue.
70

In witness whereof, I have hereunto set my hand this thirtieth day of April, 1904.

HERMANN LEMP.
